RICHARD P. SIMMONS, OF NEW YORK, N. Y.

PERCUSSIVE WELL DRILLING APPARATUS

Application filed October 22, 1929. Serial No. 401,446.

This invention relates to improvements in well drilling apparatus and its leading object is to provide an interlocking coupling between the drilling head and the well casing, which will enable the well engineer to shift the drill head in the well casing, or to rotate the casing and the drill head, while the latter is prevented from turning in the casing, so as to perform various independent 10 drilling operations, in any successive order conceived to be necessary in prosecuting the construction of the well.

Another object of the invention is the provision of improved means for interlocking the drilling head in the follower well casing, so that the drill head will never drop out of alignment of the well casing and become lost in any pockets in the path of the well bore, or become partly displaced in the lower end 20 of the well casing, so that freedom of operation, or withdrawal, would be obstructed or defeated.

A further object of the invention is the provision of a combined well casing and drilling unit, wherein a percussive drill point can be used at the free option of the well engineer, or a core barrel, with suitable drilling means thereon, can be used, and percussive action against either drilling means accomplished in the casing, without causing 30 relative rotative movement of one within the other, but permitting rotative movement of the combined well casing and drill unit in the well bore.

A further object of the invention is the provision of a well casing and drill head unit, wherein the drill will be forcibly held to operate in a predetermined vertical plane, against any tendency to be deflected to an 40 inclined or other plane, by the action of inclined rock strata, or boulders or rocks intercepting the path of the drill.

It is well known that deep wells seldom extend in a true vertical plane into the 45 ground, and that many of them are as much as forty-five degrees out of the vertical. This is undoubtedly caused by the fact that the drill points employed are deflected by the unequal resistance which inclined rock strata, or obstructing boulders or stones present, and

once deflection of the drill head starts, it continues at an increasing angle.

The more a well casing is out of the vertical plane, the more expensive will it be to construct a well of given depth, the more difficulty and costly will it be to operate, and the more frequent will be the loss of equipment during construction or operation.

When the axis of the well casing bends from a true vertical plane, increased effort 60 may be applied to advancing the casing, by successive coupling operations, and manipulation of the casing for drilling purposes becomes increasingly difficult and costly. The 65 length of the well bore increases as it is deflected from a true vertical plane so much, that the total length may be increased by fifty-percent of the vertical distance between the bottom of the well and its entrance, where 70 the inclination of the well is forty-five degrees. This naturally adds very greatly to the cost of drilling the well and may determine that abandonment of further drilling operations should be made.

The present invention provides a practical 75 means for holding the drilling unit to a vertical plane, so that a minimum of deflection, if any, is allowed in the progressive deepening of the well bore.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawings, which latter 85 show an embodiment of the invention as at 90 present preferred.

In the drawings:—

Fig. 1 is a vertical sectional view through the combined equipment, showing the hammer in its seat position on the anvil, and the 95 plane cutting bits in their cutting positions.

Fig. 2 is a similar view, showing the cutting bits retracted, or withdrawn from cutting positions.

Fig. 3 is a side elevation of the percussive 100

drill head removed from the well casing, showing the keyways and keys thereof.

Fig. 4 is a broken perspective view of the well casing.

5 Fig. 5 is an enlarged vertical sectional view through the ball bearings swivel heads of the anvil and hammer.

Fig. 6 is a perspective view on an enlarged scale of the percussive drill point.

10 Fig. 7 is a transverse sectional view taken on line 7—7 of Fig. 1, looking in the direction of the arrows.

Fig. 8 is a similar view taken on line 8—8 of Fig. 1.

15 Fig. 9 is a similar view taken on line 9—9 of Fig. 1.

Fig. 10 is a transverse sectional view taken through the drill head, on line 10—10 of Fig. 2.

20 Fig. 11 is a perspective view of the assembled group of a reamer bit and filler blades.

Fig. 12 is a transverse sectional view, taken on line 12—12 of Fig. 1, looking in the direction of the arrows.

25 Fig. 13 is a view partly in elevation and partly in section, showing combined well drilling units.

Fig. 14 is a similar view of a modified combination of well drilling units.

30 Fig. 15 is a similar view of another modified combination of well drilling units.

Referring to the accompanying drawings illustrating the invention in detail, 10 designates the drill head, which is shown to be of 35 the type generally known as a percussive drill. This drill head or unit comprises the cylindrical body 11, which is formed with an axial bore 12, the upper end of which is concentrically enlarged to provide a chamber 13. To this cylindrical body 11 the cylindrical anvil member 14 is connected by the tapered screw threaded joint 15, which is designed to permit of separation of the two parts.

40 Fig. 15 is provided with an integral tubular axial extension 16, which extends upwardly and carries a cap 17 which is threaded thereon.

The lower end of the cylindrical body 11 is 45 formed with a chamber or pocket 18 which receives the cylindrical tool holder 19, the surrounding annular flange 11a of the body 11 having a bevelled lower edge 11a', and the tool holder 19 having a bevelled shoulder 19a, to prevent dirt from packing between the meeting surfaces of the two parts. The tool holder is formed with an axial tubular extension or post 20, which slidably fits in the bore or passage 12 of the body 11, and extends into the chamber 13 thereof. Relative displacement of the tool holder in said body 50 11 is prevented by the nuts 21 and 22 threaded on the upper end of the post 20, and adapted to abut against the shoulder 13a of the chamber 13.

The lower end of a pull member 23, in the form of a pipe, is threaded or otherwise coupled to the post 20 of the tool holder, and this pull member or pipe extends slidably through the tubular post 16 of the anvil member 14, and upwardly of the screw cap 17 thereof.

The upper end of the pull member or pipe 23 extends into the housing or cylinder 24, and carries a nut 25 which is tightly threaded against the end wall 24a of said cylinder or housing 24. The pull member or pipe 23 is provided with an external shoulder 23' which engages the bottom face of the end wall 24a and limits the penetration of the pipe into the cylinder 24.

The cylinder 24 is provided with a swivel head which includes the cap 26, which is bolted to the ring 27, by means of the screw bolts 26a. This ring is formed with a horizontal portion 26b which overlies the ball bearing ring 28, disposed against the upper end of the housing or cylinder 24. The ring is held in place by means of the plug ring 29, which is secured by the screw bolts 29a directly to the end of the cylinder 24.

This cylinder 24 is provided with three openings 30, 31, and 32, in its wall. In the opening 30, an air pipe 30a is disposed, and is held in place by means of the threaded tubular clamping plug 30b. This air pipe or hose also extends through the opening 30c formed in the enclosing cylinder 33, and thence upwardly. In the air opening 31 an air hose or pipe 31a is disposed and it is held in place by means of the threaded tubular clamping plug 31b. The air hose 31a also extends through the opening 31c in the enclosing cylinder 33, and thence upwardly. Through the opening 32 the air hose 32a extends, and it is held in place by the threaded tubular plug 32b. This air hose also extends through the opening 32c in the cylinder 33, and thence upwardly.

The cylinder 33 is coupled to the cylinder 24 by means of the lower end plate 34 and the retaining bolts 34a. This end plate 34 is formed with an integral flange 34b which engages the packing material 34c disposed in the recess 34d formed in the cylinder 33. (An upper end ring 35 is connected to the cylinder 24 by means of the bolts 35a, and said end plate 35 is also formed with an integral flange 35b, which engages the packing material 35c disposed in the recess 35d of the cylinder 33.

The entire cylinder 24 and the parts associated therewith, as described, are enclosed by the tubular hammer 36, which is formed with an axial bore 37 through which the tubular extension 16 of the anvil 14 projects. The upper part of the hammer bore 37 is enlarged to provide a chamber 38 in which the cylinder 24 and its associated parts work, and the lower part of this chamber is reduced 130

to receive the screw cap 17, against which said cap abuts to limit the play of the hammer. This hammer slides in the tubular extension 39 connected by the screw threaded 5 joint 40 with the tubular body 11.

The upper end of the tubular hammer is provided with a swivel head which comprises the ball bearing ring 41, the flanged ring 42, which is held in place by the plug end plate 10 43 through the medium of screw bolts 43a. A cap 44 is secured to the flanged ring 42, by the screws 44a.

The cap 26 is equipped with an eye 26' to which the pull and lowering cable 45 is connected, and is further equipped with vertical rods 46 and 47 which extend upwardly through the cap 44 and plug end plate 43, thus locking the two caps against relative rotation.

20 The hoisting cable 45 extends through the guide 44a of the cap 44 to the surface of the well. The cap 44 is also provided with eyes 44b and 44c to which the hoisting cables 48 and 49 are connected.

25 The lower end portion of the tubular body 11 is provided with transverse slots 11e, in which the movable reamer bits 11f are mounted. These reamer bits are of segmental construction, as shown in Fig. 11, and are 30 each provided with a slot 11g in its inner end and confronting key lugs 11h and 11i. These lugs slidably engage the cam grooves 20a formed in the opposite faces of the integral fins marked 20b in Fig. 6 of the shank 35 or post 20, of the tool holder. These cam grooves include the upper vertical portions 20c, the intermediate outwardly and downwardly inclined portions 20d, and the lower vertical portions 20e. The fins just mentioned work in slots of corresponding number 40 formed in the lower end of the body 11 above the chamber or pocket 18 thereof, as shown in Fig. 2. The key lugs have free sliding movement with the cam grooves so that they 45 will be withdrawn into the vertical and innermost portions of the cam slots. When the key lugs engage the inclined upper ends 50 of the cam slots, the outer ends of the reamer bits will be withdrawn inwardly of the plane

This drill bit is shown to be formed with earth passages 19e which enter from opposite sides of the tapered drill bit or point and converge upwardly to communicate with the bore 19f of the drill point, and thus conduct earth to the bore 20' of the tool holder shank or post 20.

The tubular body 11 is provided with external longitudinal keys 11j, which extend from the upper part of the body downwardly 75 in parallel radially spaced relation to each other, so as to provide keyways 11k of similar number and shape. The lower end portions of the keys 11j are tapered at 11j' and the upper ends of the keyways are tapered at 11k'.

The well casing consists of a plurality of tubular sections 60, which may be an indefinite number, and which are coupled by screw threaded joints 61', or otherwise to each other, to permit of easy splicing in vertical line formation. These casing sections are coupled to the bottom casing section 61, which is formed with a series of longitudinal, parallel, and radially spaced keys 62 and keyways 63 therebetween, of similar design to the keys and keyways of the tubular body 11 of the drill unit. There is this difference, however, that the keys 62 are formed with transverse keyways 62a, to permit of additional locking means to engage the same.

The lower end portion of the casing section 61 is formed with a bevelled terminal 61" which is adapted to enter the bevelled grooves 61b in the reamer bits 11f, and 61c in the 100 filler blocks 50 and 51, so that the reamer bits are held in their outer cutting positions when the casing section 61 and the other sections coupled therewith are seated upon the reamer bits and the filler blocks.

When it is desired to withdraw the drill head, the well casing is slightly raised, to disengage the bevelled lower terminal 61" of said section 61, from the reamer bits and 110 filler blocks, by raising the same, with suitable hoisting means, not shown. The tool holder is then dropped by slackening up on hoisting cable 48 connected with the eye 44b of the cap 44, and this causes the fins 20b to be shifted longitudinally with their cam 115 grooves, and this action will retract or withdraw the reamer bits from their extreme outward or cutting positions, to the position shown in Fig. 2, when the cutting ends thereof will be inwardly of the vertical plane of the outer face of the body 11, thus permitting this body, together with the percussive bit point to be wholly removed from the well casing, which remains in the well, to support the earth against caving in, and to again receive the equipment.

The percussive drill head 19 is driven into the ground by the force of the hammer 36, the raising and releasing of which progressively advances the drill head 19 into the ground, displacing the earth and rock around the path of the well, so that the drill head will continue to advance.

When the equipment is withdrawn from the well casing the cylinder 24 may be opened by the removal of the cap members connected to its top, and it will be found that the interior of the cylinder has been filled with earth. By timing this withdrawal for different periods of the descent of the drilling head the geological cross section through the ground in which the well is being constructed may be reproduced and interpreted.

Whenever material is encountered which is best excavated by the use of a core barrel, the percussive drill point may be removed from the lower end 19 of the body 11, and a core barrel B connected to the tapered female thread of the tool holder. This core barrel would then be subject to the percussive action which would be developed by the raising of the hammer and its release to fall by gravity against the anvil.

The core barrel is equipped with drill bits B^c adapted to drill the ground or rock encountered by percussive or rotary action. Rotary drilling action is developed by the manual turning of the well casing, which insures the turning of the whole drill unit, including in this assembly the core barrel, and the turning of the drill bits B^c of the core barrel by the manual rotation of the casing and drill head. At the same time that the well casing is being turned to produce a rotary drilling action, through the medium of the bits B^c, the percussive action of the gravity actuated hammer may be maintained against the anvil 14, thus causing the rotating drill bits B^c to shatter the rock or material encountered by a combined rotary and percussive attack. Instead of the manual percussive hammer action described I may employ a pneumatic hammer unit B to produce the required percussive action against either the percussive drill point, or the rotary core barrel and its drill bits.

The longitudinal interlocking between the drill unit and the enclosing well casing permits of the replacement of any particular drill unit or other equipment, with any other equipment which may be found useful, and the relative longitudinal shifting of the enclosed unit, or the combined rotation of the whole in the well, to produce any action which can be best accomplished by rotative movement. In all cases relative rotation of the enclosed equipment in the well casing is prevented.

In drilling through the various materials encountered in the completion of a deep well, the resistance to drilling, and the difficulty of removing the earth or rock loosened by the drilling, varies from time to time and this variation calls for the use of tools or drilling units best adapted for performing the particular work most needed in any condition.

The improved percussive head when interlocked with the well casing will be prevented from being displaced therefrom, by downward movement, and the cutting tools carried thereby will be supported below the lower end of the well casing, to be expanded to cutting position or retracted or withdrawn from cutting position, while to the lower end of the housing of the percussive head an additional unit or units may be coupled, as shown in Fig. 13.

In this figure a core barrel unit B is connected to the percussive head unit A, by means of the coupling union or joint B^a. This core barrel unit is disclosed fully in my co-pending application for patent, Serial No. 401,447, filed October 22, 1929. When it is desired to withdraw any unit coupled to the percussive drill head, the reamer bits are first retracted or moved inwardly, thus permitting the structure extending below the lower end of the casing to be lifted through the casing.

The device embraces an earth receiving and holding chamber B^a, and flexible metal strips B^b, which are movable across this chamber to trap earth forced into the same in the progress of the core barrel through the path of the well to be drilled. These metal strips are shifted by means of mechanical elements enclosed by the housing of the core barrel unit B, and operable from the surface of the well. The lower end of the core barrel unit B is equipped with a rotary drill head B^c, which may be rotated when the well casing is turned, and which may shatter the material in its path under the percussive action set up with the percussive head.

When the core barrel has been filled with earth or the debris of drilling the two units A and B may be withdrawn through the well casing leaving the same in place. The unit B is small enough in diameter to easily pass through the lower end of the well casing when the reamer tools are retracted, as shown in Figs. 13, 14 and 15.

The percussive head cuts a circular plane for the free lowering of the well casing. When the units A and B are withdrawn the wall of the well bore would have a tendency to collapse, especially if composed of materials having low cohesive properties, and in order that this collapse be prevented the percussive head is supplied with an air jet 80, which discharges compressed air into the well chamber formed by the core barrel unit. This jet is supplied with air from the head of the well, by means of the conduit 31^a or 32^a.

In Fig. 14 the percussive unit A is combined with the under reamer unit C and the core barrel unit B, with the latter placed under the unit C. This under reamer unit C is disclosed in a copending patent application

filed by me October 23, 1929, Serial No. 401,925.

The under reamer includes a housing C^a which is provided with a debris holding chamber and expansive and retractive reamer tools C^b, which are shifted from one position to the other by means of the toggle joint C^c, which is operated by mechanism concealed by the housing of the unit C. This 10 under reamer cuts a circular plane for the well casing, and its cutting tools are of the kind which rotate around their own axis, so they are adapted for cutting harder materials than is the case with the cutting tools of 15 the percussive head, which do not move when forced to the cutting position, with relation to the unit A.

In Fig. 15 the percussive unit A is combined with a core barrel unit CC, which is 20 constructed to trap rock core in its holding chamber CC^a. This is accomplished by means of a lever CC^b, which is mounted to move through a slot in the wall of the inner cylinder which forms the chamber CC^a. This 25 lever is shifted from one position to another position by means of the cam CC^c formed in the outer cylinder CC' of said core barrel. The lower end of the unit CC is equipped with a drilling head CC^d.

30 The hereinbefore described construction admits of considerable modification without departing from the invention; therefore, I do not wish to be limited to the precise arrangements shown and described, which are, 35 as aforesaid, by way of illustration merely. In other words, the scope of protection contemplated is to be taken solely from the appended claims, interpreted as broadly as is consistent with the prior art.

40 I claim as new:—

1. A well drilling apparatus consisting of a housing, wall cutting tools slidable in said housing, means slidable in the housing for shifting the cutting means to cutting positions and withdrawing the same from cutting positions, means for coupling the housing in a well casing to support the housing against downward movement therein and against relative rotative movement, a drill 45 element coupled to said shifting means, and a reciprocating hammer in said housing.

2. A well drilling apparatus consisting of a housing, wall cutting means slidable in said housing, a drill point, vertically shiftable cam 55 means coupled to the drill point for shifting the cutting means inwardly and outwardly of the housing, a well casing, means between the housing and the well casing for interlocking the two to each against relative 60 rotative movement and to permit of relative sliding movement, and means in said housing for producing a percussive movement against said drill point.

3. A percussive well drilling apparatus consisting of a well casing, a cylinder in the low-

er end of the well casing, means for limiting the downward movement of the cylinder in the well casing, well reaming cutters slidably mounted in the cylinder, means operable from the head of the well for operating said cutters to shift the same outwardly of the well casing, said cylinder having a dirt holding chamber, and a drill point carried by said cylinder and provided with dirt passages.

4. A well drilling apparatus comprising a 75 housing, wall cutting tools slidable in said housing, means for interlocking the housing with a well casing to retain it in position in the latter, a drilling element axially movable in the housing and operatively connected with the cutting tools to radially project or retract them depending on the direction of axial movement, and means for bodily driving the housing to effect cutting action of the drilling element.

5. A well drilling apparatus comprising a 80 housing, wall cutting tools slidable in said housing, means for interlocking the housing with a well casing to retain it in position in the latter, a drilling element axially movable in the housing and operatively connected with the cutting tools to radially project or retract them depending on the direction of axial movement, and means for bodily driving the housing to effect cutting action of the drilling element, the housing having 85 an abutment engaged by the drilling element.

6. A well drilling apparatus comprising a 90 housing, wall cutting tools slidable in said housing, means for interlocking the housing with a well casing to retain it in position in the latter, a drilling element axially movable in the housing and operatively connected with the cutting tools to radially project or retract them depending on the direction of axial movement, and means for bodily driving the housing to effect cutting action of the drilling element, the housing having an abutment 95 engaged by the drilling element when the housing is being driven, and the wall cutting tools being radially projected when the drilling element engages such abutment.

7. A well drilling apparatus comprising a 100 well casing, a percussive drilling unit having an interlocking connection with the well casing to preclude relative angular or turning movement between the two and prevent the former dropping out of the lower end of the latter, a core barrel coupled to the drilling unit and having a limited axial movement with respect to the same, and wall cutting tools disposed between the core barrel and the drilling unit and extended or retracted 105 when the core barrel is moved axially with reference to the drilling unit.

8. A well drilling apparatus comprising a 115 well casing, a percussive drilling unit having an interlocking connection with the well casing to preclude relative angular or turning 120 movement between the two and prevent the former dropping out of the lower end of the latter, a core barrel coupled to the drilling unit and having a limited axial movement with respect to the same, and wall cutting tools disposed between the core barrel and the drilling unit and extended or retracted 125 when the core barrel is moved axially with reference to the drilling unit.

- movement between the two and prevent the former dropping out of the lower end of the latter, a core barrel coupled to the drilling unit and having a limited axial movement 5 with respect to the same, and wall cutting tools disposed between the core barrel and the drilling unit and extended or retracted when the core barrel is moved axially with reference to the drilling unit, the core barrel 10 at its lower end being provided with cutting elements and being also provided above said cutting elements with an earth receiving chamber.
9. A well drilling apparatus comprising a well casing, a percussive drilling unit having an interlocking connection with the well casing to preclude relative angular or turning movement between the two and prevent the former dropping out of the lower end of 15 the latter, a drilling element carried at the lower extremity of said unit and movable axially with respect thereto and engaging an abutment in one of the extreme positions of axial movement, and an underreamer carried 20 by the unit and radially extensible and contractible and having an operative connection with said drilling element to be extended or retracted when the element is moved axially with respect to the unit.
- 25 10. A well drilling apparatus comprising a well casing, a percussive drilling unit having an interlocking connection with the well casing to preclude relative angular or turning movement between the two and prevent 30 the former dropping out of the lower end of the latter, a drilling element carried at the lower extremity of said unit and movable axially with respect thereto and engaging an abutment in one of the extreme positions of 35 axial movement, and an underreamer carried by the unit and radially extensible and contractible and having an operative connection with said drilling element to be extended or retracted when the element is moved axially 40 with respect to the unit, the abutment engaged position of the element effecting extension of the underreamer.
- 45 11. A well drilling apparatus comprising a housing, wall cutting tools slidable in said housing, means for interlocking the housing with a well casing to retain it in position in the latter, a drilling element axially movable in said housing and operatively connected with the cutting tools to radially project or retract them depending on the direction of axial movement, an anvil detachably engaged with the housing at the upper end and having an upstanding axially arranged extension, means for imparting independent 50 axial movement to the drilling element having a member extending through said anvil and through said extension, and an impact tool disposed in surrounding relation to said extension.
- 55 12. A well drilling apparatus comprising a
